UNITED STATES PATENT OFFICE

2,022,817

CENTRIFUGAL BOWL FOR SEPARATING
HEAVY SLUDGE AND SOLIDS FROM
LIGHTER LIQUIDSGeorge J. Strezynski, Poughkeepsie, N. Y., as-
signor to The De Laval Separator Company,
New York, N. Y., a corporation of New Jersey

Application December 29, 1933, Serial No. 704,482

13 Claims. (Cl. 233—46)

My invention is an improvement in bowls for separating heavy sludges or solids from lighter liquids and discharging them through openings in the bowl wall.

5 The object of my invention is to provide, in a bowl with outlets at its maximum diameter for the escape of heavy sludge or slimy solids, simple and reliable means, which may be either automatic or under the control of the operator, for opening and for closing such outlets.

In an application filed by me September 27, 1933, Serial No. 691,111, I disclose a structure effectively accomplishing the above objects. It comprises a centrifugal bowl provided with an outlet through its peripheral wall, a hollow liquid-containing valve body contained in a tubular guide chamber communicating with the separating chamber of the bowl, and floatable back and forth in radial direction in the liquid entering said chamber. In its outer position the valve, which itself is provided with a restricted escape orifice at its tip through which liquid continually escapes through said bowl wall outlet, seats against said outlet. When the valve moves inward, said outlet is opened to permit the escape of accumulated sludge. The valve moves outward when it is more or less filled with liquid and moves inward when it is more or less emptied of liquid. The valve may receive liquid from the separating space of the bowl until sludge has accumulated on the peripheral wall of the bowl to a predetermined depth, in which case the operation is automatic; or it may receive a special control or supplemental liquid whose inflow is through a special feed tube controlled externally of the bowl. The first operation is open to the objection that there is a continuous loss, through said restricted orifice, of light liquid which is often valuable. The second operation avoids this objection, but is open to the objection that any excess of the control liquid over that which can escape through said restricted orifice, overflows the inner end of the valve body and mixes with and contaminates the liquid being treated.

45 The present invention involves the use of a supplemental liquid for controlling the position of the valve and includes means whereby the operator can control the opening and closing of the valve without either loss or contamination of the valuable liquid which is being treated or separated in the centrifuge.

In the accompanying drawing, which illustrates an embodiment of my invention, Figure 1 is a cross section of one of the bowls a little to the

near side of the center, and Figure 2 is a detail to a larger scale of the control valve.

a is a bowl shell having a top b and containing a tubular shaft c, a nest of separating discs d, a top disc e, and a member f enclosing a chamber g. The bowl is supported and driven by a spindle h revolving in a bearing i. The liquid to be treated enters through a feed tube j, the light liquid escapes at k, the heavy liquid at x and the still heavier sludge, etc. at m. A tube n, passing through the feed tube j discharges into the chamber g and has around its lower portion a deflector o to prevent liquid from feed tube j entering the chamber g.

At the inner end of the port m there is a valve 15 seat p against which the conical end of a valve q fits to close the port. On the valve there are lugs r which centralize it in a radially located tube s which surrounds, protects and guides it and which has its inner end nearer to the center 20 of the bowl than the outlet k for light liquid so that liquid will not escape from the inner end of tube s. Through the apex of the valve there is an orifice t throttled by a screw u and at the 25 other end there is a lip v which extends over the end of the tube s. A tube w, leading from the chamber g, discharges into the valve q.

In operation, liquid to be treated is fed through tube j into the tubular shaft through which it flows to the inter disc spaces in the bowl, where 30 it is separated into three components. The light liquid flows toward the center and escapes at k. The heavy liquid flows toward the outside, around the edge of the top disc and then inward to the outlet x, where it escapes. Sludge, heavier than either of the liquids, collects against the bowl wall. At the same time a continuous flow of water or other operating liquid is fed through tube n, chamber j and tube w into the valve at 35 a rate a little faster than the leakage through the throttled orifice t. The excess escapes at the lip v and can be caught and conducted away. When he desires to have the ports m open, the operator shuts off the flow of valve-control liquid, 40 that in the valve leaks out through the orifice t, and, after the escape of a predetermined quantity of such liquid through said orifice, the valve floats toward the center, leaving the port m open. When the sludge has been discharged the 45 operator turns on a heavy flow of control liquid to fill the body and close the valve and then reduces it to a little more than needed to keep it full.

If the mixture of a little water with the sludge 50

is objectionable it will generally be possible to select a control liquid that will not be objectionable.

From the foregoing it may be seen that I have provided a means, including the use of a supplemental liquid, for controlling valves for ports in a bowl wall that does not involve any loss of valuable liquid or any contamination of valuable liquid by the supplemental valve operating liquid.

10 The flow of liquid for operating the valve may be controlled by hand or by an automatic timing device to give definite open and closed periods for the valve.

15 What I claim and desire to protect by Letters Patent is:

1. The combination with a centrifugal bowl having an outlet relatively near its axis for escape of a lighter component and a port through its wall for escape of a heavier component, of port-closing means including a buoyant valve member extending nearer to the bowl axis than the bowl outlet for a lighter component and having from its inner end an overflow passage leading outside the bowl and from its outer end a restricted orifice leading to the port, and means controllable exteriorly of the bowl to intermittently flow liquid into said valve.

2. The combination with a centrifugal bowl having an outlet for liquid and a port through its wall, a valve seat at the inner end of the port and a tubular member, coaxial with said port, communicating with the interior of the bowl and extending radially to a point nearer the axis than the outlet for liquid, of a valve member, within, protected and guided by said tubular member, having a conical end adapted to fit said seat and close the port and having an orifice therethrough and a hollow body extending nearer to the axis than said outlet for liquid and having a discharge lip overhanging the inner end of the guiding member, and means controllable exterior of the bowl to intermittently flow liquid into said valve body.

3. In a centrifugal bowl provided with an outlet through its peripheral wall, a hollow floating valve member movable outward to close said outlet when weighted with a predetermined amount of contained liquid and provided with an escape orifice at its outer end through which said liquid may continually escape, means providing a passage through which liquid may be fed from outside of the bowl direct to said valve member at a rate in excess of the rate of outflow through said escape orifice, and means for overflow of excess liquid from the inner end portion of said valve member to outside the bowl, said valve member being floatable inward to open said bowl wall outlet, after the feed of said liquid to said valve member is arrested, by reason of the continued escape of liquid through said valve orifice.

4. In a centrifugal bowl provided with an outlet through its peripheral wall and with an outlet relatively near the axis of the bowl for outflow of lighter separated liquid, a chamber communicating with the separating space of the bowl, a hollow valve member floatable in said chamber in liquid received in said chamber from the separating space of the bowl and adapted when moved outward to close said outlet and so movable outward when weighted with a predetermined amount of contained supplemental liquid and provided with an escape orifice at its outer end through which such contained liquid may continually escape, the inner end of said valve member being nearer the center of the bowl than

said outlet for lighter liquid, means controllable externally of the bowl to feed supplemental liquid to said valve member, and means providing for overflow to outside of the bowl of supplemental liquid from the inner end portion of the valve member, whereby when supplemental liquid is fed into the bowl in excess of its rate of escape from said orifice the valve member will be held in position to maintain said bowl wall outlet closed and whereby when the feed of supplemental liquid is arrested the escape of same through said orifice will cause the valve member to lighten and float inward and open said bowl wall outlet.

5. In a centrifugal bowl provided with an outlet extending from and communicating with the peripheral space of the bowl, a hollow member comprising a valve and positioned between said peripheral outlet and the axis of the bowl, said member being movable outward to seat the valve and close communication between the peripheral part of the bowl and said outlet and movable inward to unseat the valve and open said communication, and a liquid admission conduit extending from outside the bowl and communicating, independent of the separating space of the bowl, with said hollow member and through which liquid may be supplied to said hollow member, and means allowing discharge of liquid from said hollow member, whereby, by varying the weight of its contained liquid, said valve is caused to move into and out of position to close said outlet.

6. In a centrifugal bowl having a port through its wall, the combination of a chamber positioned between said port and the axis of the bowl and in communication with, and adapted to receive liquid from, the separating space of the bowl, a hollow buoyant valve within said chamber and floatable in the liquid contained therein to open and close said port, and a liquid-admission conduit extending from outside the bowl and communicating, independent of the separating space of the bowl, with the interior of said valve and through which liquid may be supplied to said hollow valve, and means allowing discharge of liquid from said hollow valve, whereby, by thus varying the weight of its contained liquid, said valve is caused to float toward and from port-closing position.

7. In a centrifugal bowl having a port through its wall, the combination of a chamber positioned between said port and the axis of the bowl and in communication with, and adapted to receive liquid from, the separating space of the bowl, a hollow buoyant valve within said chamber and floatable in the liquid contained therein to open and close said port, and a liquid-admission conduit extending from outside the bowl and communicating, independent of the separating space of the bowl, with the interior of said valve and through which liquid may be supplied to said hollow valve, means allowing discharge of liquid from said hollow valve, whereby, by thus varying the weight of its contained liquid, said valve is caused to float toward and from port-closing position, and means preventing overflow of liquid from the inner end of the valve to the liquid separating space of the bowl.

8. In a centrifugal bowl having a port through its wall, the combination of a chamber positioned between said port and the axis of the bowl and in communication with, and adapted to receive liquid from, the separating space of the bowl, a hollow buoyant valve within said chamber and

5 floatable in the liquid contained therein to open and close said port, and a liquid-admission conduit extending from outside the bowl and communicating, independent of the separating space of the bowl, with the interior of said valve and through which liquid may be supplied to said hollow valve, means at the outer end of the valve allowing discharge of liquid from said hollow valve, whereby, by thus varying the weight of its 10 contained liquid, said valve is caused to float toward and from port-closing position, and means preventing flow of liquid to or from the inner end of the valve to or from the separating space of the bowl.

15 9. In a centrifugal bowl having a port through its wall, the combination of a chamber positioned between said port and the axis of the bowl and in communication with, and adapted to receive liquid from, the separating space of the bowl, a 20 hollow buoyant valve within said chamber and floatable in the liquid contained therein to open and close said port, and a liquid-admission conduit extending from outside the bowl and communicating, independent of the separating space 25 of the bowl, with the interior of said valve and through which liquid may be supplied to said hollow valve, means allowing discharge of liquid from the outer end of said hollow valve, whereby, by thus varying the weight of its contained liquid, said valve is caused to float toward and from port-closing position, and means to discharge liquid overflowing from the inner end of a filled 30 valve and preventing the flow of such discharged liquid to the separating space of the bowl.

35 10. In a centrifugal bowl provided with an outlet extending outwardly from and communicating with the peripheral space of the bowl, a hollow floating member between said peripheral outlet and the axis of the bowl and having in the end thereof nearest said axis a fluid admission opening, said member being movable radially outward to close said outlet when weighted with a predetermined amount of contained liquid, means to feed supplementary liquid to the inside of said hollow member to cause it, by reason of its thereby increased weight, to assume said outlet-closing position, and means allowing escape of said supplementary liquid when in said outlet-closing position, whereby, when inflow of supplementary liquid is arrested, said member will be lightened sufficiently to float inward and open said outlet.

40 11. In a centrifugal bowl provided with an outlet extending outwardly from and communicat-

5 ing with the peripheral space of the bowl, a hollow floating member between said peripheral outlet and the axis of the bowl and having in the end nearest said axis a fluid receiving opening, said member being movable radially outward to close said outlet when weighted with a predetermined amount of contained liquid, means controllable externally of the bowl to feed supplementary liquid to the inside of said hollow member to cause it, by reason of its thereby increased 10 weight, to assume said outlet-closing position, and means allowing escape of said supplementary liquid when in said outlet-closing position, whereby, when inflow of supplementary liquid is arrested, said member will be lightened sufficiently to float 15 inward to open said outlet.

12. In a centrifugal bowl provided with an outlet extending outwardly from and communicating with the peripheral space of the bowl, a valve seat at the inner end of said outlet, a radially 20 floating hollow member comprising at its outer end a valve adapted, when said hollow member moves outward, to be seated and thus close said outlet, guiding means for said hollow member, there being through said valve a restricted port 25 adapted to meet said outlet when the valve is seated, and means providing a passage for supplementary liquid into said hollow member, whereby said hollow member may be moved outward to seat the valve by admitting liquid there- 30 into and may be caused to float inward, after shutting off the supply of supplementary liquid, by outflow of supplementary liquid therefrom through said port and outlet.

13. In a centrifugal bowl provided with one or 35 more outlets for relatively light liquid and a peripheral outlet for sludge or heavy solids, a hollow member having a rear opening for receipt of liquid, said opening being closer to the bowl axis than any liquid outlet, said member being so 40 guided that it is adapted when filled with a predetermined weight of liquid to float outward and close said peripheral outlet and adapted to float inward and open said peripheral outlet upon reduction of weight due to escape of liquid, means 45 allowing such escape of liquid while said member is holding the peripheral outlet closed, and means to flow liquid from a source exterior to the bowl around the separating space of the bowl to said member after it floats into position to open the 50 peripheral outlet and to thereby cause it to again move into position to close the peripheral outlet.

GEORGE J. STREZYNSKI.
